CLAIM

We claim the ornamental design for portions of a foot operated electrical control, as shown and described.

DESCRIPTION

Reference is made to utility application Ser. No. 10/136,202 filed May 1, 2002 by James E. Moll and Brent A. Moll, entitled Foot Operated Electrical Control, the disclosure of which is incorporated herein by reference.

FIG. 1 is a perspective view showing front, top and right end portions of a first embodiment of our new design;

FIG. 2 is a front side elevational view thereof;

FIG. 3 is a rear side elevational view thereof;

FIG. 4 is a right end elevational view thereof;

FIG. 5 is a left end elevational view thereof;

FIG. 6 is a top plan view thereof;

FIG. 7 is a bottom view thereof;

FIG. 8 is a perspective view showing front, top and right end portions of a second embodiment of our new design;

FIG. 9 is a front side elevational view thereof;

FIG. 10 is a rear side elevational view thereof;

FIG. 11 is a right end elevational view thereof;

FIG. 12 is a left end elevational view thereof;

FIG. 13 is a top plan view thereof; and,

FIG. 14 is a bottom view thereof.

The broken line showing of the environment is for illustrative purposes only and forms no part of the claimed design.
